UNITED STATES PATENT OFFICE

2,668,315

HAIR VACUUM CLEANER

Wilbur D. Crosby, Orinda, Calif., assignor of twenty-five per cent to William L. Hillman, Orinda, and twenty-five per cent to John W. Crosby, Modesto, Calif.

Application May 1, 1950, Serial No. 159,315

2 Claims. (Cl. 15—344)

1

This invention comprises novel and useful improvements in a hair vacuum cleaner and more specifically pertains to a device for applying a suction or vacuum to hair to assist in removing dandruff, scale or the like therefrom; to apply vacuum or suction to assist in massaging; and to provide a device for producing and delivering a stream of cleansed air, heated or unheated, as desired.

The principal object of this invention is to provide an improved air blowing means which is specifically adapted for use by barbers and the like for applying a suction to the hair, scalp or other places for cleansing the same; to operate as a portable vacuum cleaner for removing cuttings of hair, dust and the like from the clothing and person whose hair has been treated.

A further important object of the invention is to provide a device in conformity with the preceding objects which is also capable of use as a means for supplying cleansed and unheated or heated air.

A still further important object of the invention is to provide a mechanism in conformity with the above mentioned objects in which the various parts thereof are of simple construction, may be easily removed or installed, and are capable of ready sterilization and cleansing as desired.

These, together with various ancillary features and objects of the invention which will later become apparent as the following description proceeds, are attained by the present invention, a preferred embodiment of which has been illustrated, by way of example only, in the accompanying drawings, wherein:

Figure 1 is a side elevational view showing a preferred embodiment of the device with a suction cone nozzle applied thereto;

Figure 2 is a vertical central longitudinal sectional view of the device shown in Figure 1, illustrating portions of the interior construction of the same;

Figure 3 is a fragmentary top plan view of the device shown in Figures 1 and 2;

Figure 4 is a fragmentary view of the underside of the device or opposite side of the device shown in Figures 1-3;

Figure 5 is a horizontal sectional view taken substantially upon the plane indicated by the section line 5—5 of Figure 2;

Figure 6 is a horizontal sectional view taken substantially upon the plane indicated by the section line 6—6 of Figure 2; and

Figure 7 is a plan view of the filtering element forming a part of the invention.

2

Referring now more specifically to the accompanying drawings, wherein like numerals designate like parts throughout the various views, it will be seen that the invention includes an electric motor of any desired type and having a casing 10, this casing constituting a handle by means of which the apparatus may be manipulated, the casing having a suitable opening for the reception of an electric conductor 12 by means of which the electric motor is supplied with power, under the control of a pair of switches indicated generally at 14 and 16, one of the switches controlling the operation of the motor and the other switch controlling the operation of an electric heating element as set forth hereinafter.

Preferably, the motor casing 10 is provided with an annular band or shoulder portion 18 for a purpose which will be later apparent.

20 The motor is provided with the customary armature (not shown), the same including an axially extending shaft 20, upon which is detachably secured a fan assembly 22 of any desired character. This fan is preferably of the centrifugal type, and the same may conveniently consist of a circular disk or plate 24 having a hub portion 26 which is removably secured upon the shaft 20 as by a set screw or the like 28, the disk 24 being provided with a plurality of

30 radially off-center vanes or blades 30.

The apparatus further includes a cylindrical casing 32 which is adapted to be slidably received upon the outer end of the motor casing 10, to have its inner end abutted against the annular collar 18 formed upon the casing 10, the sleeve 32 being detachably secured upon the casing 10 as by a set screw or the like 34.

35 The apparatus is provided with a suction nozzle which may be of plastic, metal or any other suitable material, the nozzle being indicated by the numeral 36 and having a suction or inlet end 38 communicating with a tapering passage 40 within the nozzle which extends from the inlet end to the rear end of the nozzle.

40 The rear end of the nozzle consists of a cylindrical portion 42 which is disposed in any suitable angle with respect to the nozzle 36, and which slidably embraces the open outer end of the sleeve 32, this inner end being provided with a bayonet slot 44 of conventional design for detachable engagement by a fastening screw 46 which is screw-threadedly engaged in the end of the sleeve 32.

45 By means of the bayonet slot and the screw, it is obvious that the nozzle may now be readily attached to or removed from the sleeve 32, which latter in turn is releasably se-

cured to the casing 10 of the motor. The outer end of the sleeve 32 constitutes a centrifugal pump casing in which is received the centrifugal fan 22, and into which communicates the passage 40. Received within the outer end of the sleeve 32, and disposed within the outlet of the cylindrical portion 42 of the nozzle 36, is a disk 48 constituting a partition or baffle, and which is provided with a central aperture or opening 50. This opening 50 loosely receives the shaft extension 29, and constitutes the inlet to the centrifugal fan 22, this disk or partition being held in place by a ring-like member 52 retained by a set screw or the like 54.

Removably seated in a slot in the ring 52 and in a registering slot in the cylindrical portion 42 of the nozzle 36, is a removable tray 56 which is open at its top and its bottom, and is provided with a conical filtering screen 58 secured thereto in any desired manner.

The arrangement is such that when the tray is in place, the screen will be disposed across the outlet of the passage 40 of the nozzle, so that air passing through the nozzle will be filtered or screened before the same passes through the opening 50 into the pumping chamber of the centrifugal fan 22. This will prevent the passage of dirt or the like, bobby pins, or other foreign matter through the fan or pump when the device is operated to clean hair.

From the pumping chamber, the air passing through the nozzle and fan is passed through a discharge passage 60 in the material of the nozzle 36, to an outlet opening or vent 62. A suitable electric resistance heater 64 of any desired character is disposed in the passage 60, for heating the air passed therethrough, this electric heater being connected to the switch 16 in any desired manner, not shown.

From the foregoing it will be seen that there has been provided a device which may be selectively employed to provide a source of suction for drawing air through hair or the like for cleansing the same; for operating as a vacuum cleaner or the like as desired, this air drawn through the device being discharged through the vent 62. Alternatively, the device may be employed to deliver heated and cleansed air, as for drying hair or the like, by energizing the heating element 64 through the switch 16, and actuating the motor through the switch 14, whereby air drawn through the nozzle 40 will be cleansed by the screen 58, and discharged across the heating element 64 from the vent 62.

It will further be seen that a novel hair cleaning element has been provided in the form of the tray 56 which may thus be readily withdrawn from its slot in the nozzle 36, when it is desired to cleanse, sterilize or replace the screen 58.

As shown in Figure 1, a suitable closure 66 may be provided for that portion of the nozzle which houses the heating element 64, so that by the removal of fastening screws 68, access may be had to the heating element for inspection, repair or cleansing of the same.

The extremity 38 or inlet of the nozzle 36, is preferably provided with a suction cup attachment, the same consisting of a rubber or similar bushing 70 having one end provided with resil-

ient fingers or the like 72, and its other end having a socket 74 adapted to embrace the extremity of the nozzle 36. It will now be seen that when the device is assembled in the manner shown in Figures 1 and 2, the device may be manipulated to cause the flexible fingers 72 to scrub or massage the scalp or hair and dislodge dandruff or scale therefrom while drawing a current of air through the same to remove the dislodged particles and thereby properly cleansing the hair. During this operation the screen 58 will serve to prevent the ingress of this foreign material into the air stream flowing through the centrifugal or compressor.

From the foregoing, the construction and operation of the device together with as many advantages will be readily apparent and further explanation is believed to be unnecessary. However, since numerous modifications and changes will readily occur to those skilled in the art after a consideration of the foregoing specification and accompanying drawings, it is not desired to limit the invention to the exact construction shown and described, but all suitable modifications may be resorted to, falling within the scope of the appended claims.

Having described the invention, what is claimed as new is:

1. A vacuum cleaner of the hand type for cleaning hair and scale comprising an electric motor having a drive shaft, said motor including a casing as a part thereof, a nozzle body and means for mounting said nozzle body upon said motor casing whereby the latter constitutes a hand grip means for supporting the cleaner, a centrifugal fan mounted upon the drive shaft of said motor, said nozzle body having air inlet and discharge ports, passages in said nozzle body connecting said ports with the suction and discharge sides of said centrifugal fan, said nozzle body having a flexible nozzle on one end thereof communicating with said air inlet port, said nozzle having flexible fingers for massaging the scalp, said ports being disposed in laterally offset position on opposite sides of said nozzle body and having their axes in alignment and at an angle with respect to the longitudinal axis of the motor.

2. The combination of claim 1 wherein said nozzle body has an opening into said air inlet port passage, a tray removably mounted in said opening, a screen carried by said tray extending across said air inlet passage.

WILBUR D. CROSBY.
